DESIGN FOR A FLOWER HOLDER OR SIMILAR ARTICLE

Robert F. Duryea, Palo Alto, Calif.

Application November 20, 1935, Serial No. 59,673

Term of patent 7 years

To all whom it may concern:

Be it known that I, Robert F. Duryea, a citizen of the United States, residing at Palo Alto, in the county of Santa Clara and State of California, have invented a new, original, and ornamental Design for a Flower Holder or Similar Article, of which the following is a specification reference being had to the accompanying drawing, forming part thereof.

The flower holder is substantially round and symmetrical throughout

The figure is a perspective view of the flower holder or similar article, showing my new design.

I claim:

The ornamental design for a flower holder or similar article, as shown and described.

ROBERT F. DURYEA.
